MATTRESS BORDER OR THE LIKE

Lawrence Gerald Koch, Chicago, Ill., assignor to Spring-Air Company, Holland, Mich., a corporation of Michigan

Application March 14, 1949, Serial No. 1,387

Term of patent 7 years

(CL. D5—2)

To all whom it may concern:

Be it known that I, Lawrence Gerald Koch, a citizen of the United States of America, residing at Chicago, in the county of Cook and State of Illinois, have invented a new, original, and ornamental Design for a Mattress Border or the like, of which the following is a specification, reference being had to the accompanying drawing, forming a part thereof, in which

Fig. 2 is a cross-sectional view taken on the line 2—2 of Fig. 1; and

Fig. 3 is a cross-sectional view taken on the line 3—3 of Fig. 1.

I claim:

The ornamental design for a mattress border or the like, as shown.
